DESK PAD AND HOLDER**Louis L. Bresler, 4328 Colombia Ave., Hammond, Ind.****Filed Aug. 9, 1957, Ser. No. 677,261****5 Claims. (Cl. 281—15)**

This invention is particularly concerned with improvements in a holder for supporting on a desk or similar surface in convenient position for use a note pad, order book or any other group of sheets which are bound or otherwise joined along a common edge to a relatively stiff backing member.

It is a general object of the invention to provide a pad of note paper or the like and a holder therefor which is adapted to support the pad on a desk or other surface in a position to enable convenient and easy writing thereon and to hold the pad against displacement during use while permitting removal of one or more pages or sheets, as desired.

It is a more specific object of the invention to provide a holder for a note pad or other group of sheets which are connected along a common edge to a backing member wherein the holder is provided with a pocket having an opening on its upper surface for receiving the backing member on the pad to frictionally hold the pad against displacement relative to the holder when it is written upon or sheets are torn therefrom.

It is a further object of the invention to provide a note pad which is characterized by a group of sheets bound along one edge to a relatively stiff backing board, and a holder therefor wherein the holder comprises a base member and a top cover member having a generally rectangular slot therein which opens into a pocket for receiving the backing board of the pad and wherein the pad is provided with a filler strip of substantially the same thickness as the cover member which is arranged along the edge of the backing board to which the group of sheets is connected so that when the backing board is passed through the slot and into the pocket in the holder the filler strip will be seated in the slot and prevent shifting of the pad while at the same time the surface of the filler strip will be flush with the surface of the cover adjoining the slot thereby providing a smooth supporting surface for writing on the bottom sheets in the pad as the pad is used and the top sheets are removed therefrom.

It is another object of the invention to provide a note pad and holder therefor wherein the holder is provided with a top cover member having a rectangular aperture through which the backing member on the pad may be passed and wherein the pad has a rectangular filler strip of slightly smaller dimensions than the aperture which is located on the inner surface of the backing board so that when the backing board is passed through the slot the filler strip will be seated in the aperture with its uppermost surface flush with the adjoining portions of the cover member whereby to prevent displacement of the pad on the holder and to provide a smooth backing surface for writing on the last sheets of the pad when the top sheets are removed therefrom.

It is still another object of the invention to provide a note pad holder having a base plate and a top cover member which is arranged thereon to provide a pocket for the backing member of the note pad and which is

2

provided with a generally rectangular slot through which the backing member is inserted into the pocket and a locking slide mounted adjacent the slot with one end adapted to project into the slot for locking engagement

5 with the edge of the pad and with a handle forming flange on the other end which projects beyond the edge of the holder and which permits the locking slide to be moved to engage its inner end with the edge of the pad and hold the same in position in the slot.

10 These and other objects and advantages of the invention will be apparent from a consideration of the note pad and holder therefor which are shown by way of illustration in the accompanying drawings, wherein:

Figure 1 is a perspective view of a note pad and a holder therefor which embody therein the principal features of the invention;

Figure 2 is a cross section, on an enlarged scale, taken on the line 2—2 of Figure 1;

Figure 3 is a plan view of the uppermost surface of 20 the holder with the note pad removed therefrom; and

Figure 4 is a perspective view of the note pad.

Referring to the drawings, there is illustrated a note pad 10 and a holder 11 therefor which have incorporated therein structural features adapting the same for use together on a desk or other supporting surface where the note pad 10 is conveniently positioned for writing thereon or for removing one or more of the uppermost pages or sheets thereof. While the pad holder 11 is shown in the drawings with the note pad 10 supported thereon, it will be understood that the holder 11 is adapted to be used with order pads, sales books or any group of sheets that are bound or otherwise joined together along a common edge to a suitable backing member.

The pad holder 11 comprises a generally rectangular 35 base plate 12 which is preferably formed of a relatively heavy metal and which is mounted in a rectangular opening 13 provided in a frame-like member 14, the latter being preferably formed of chipboard or similar material and the opening 13 therein being of a size sufficient to snugly receive the base plate 12. The depth or

40 thickness of the frame member 14 exceeds the corresponding dimension of the base plate 12 by a predetermined amount which will be hereinafter referred to in connection with the description of the note pad 10. The base plate 12 and the frame member 14 in which it is mounted are enclosed in a covering material which preferably

45 comprises a top sheet of leather, simulated leather, cloth or similar material 15 which is arranged with its margins folded down over the peripheral edges of the frame member 14 and turned inwardly into overlapping relation with the margins of a bottom sheet 16. Preferably, a line of stitching, which is indicated at 17, is employed to secure the sheets 15 and 16 to the frame member 14 with the stitching 17 being spaced inwardly

50 of the outer edges of the frame member 14 to form a decorative border around the entire holder. The top surface forming portion 18 of the cover sheet 15 is provided with an elongate rectangular aperture or slot 19 of substantial width and extending a substantial portion

55 of the distance across the pad holder. The slot 19 provides an opening into a pocket 20 which is formed between the uppermost surface of the plate 12 and the cover member 15 due to the difference in the thickness of the base plate 12 and the surrounding frame member 14. The pocket 20 is adapted to receive a portion of the pad 10 when the latter is positioned for use on the holder 11.

The note pad 10 comprises a bottom or outer base sheet 21 of relatively stiff material such as cardboard or the like, and an inner base member 22 which may be of 60 the same or similar material together with a group of sheets 23 of paper or like flexible sheet material in stacked

relation and positioned on the backing members 21 and 22 with the sheets and the backing members connected or joined together along one side edge 24 of the pad by a film of adhesive or an edge strip so that the stack of sheets 23 is normally retained in flat position on the backing members 21 and 22 with the sheets adapted to be removed one or more at a time from the top of the pad by pulling the same loose from the connecting adhesive film along the edge 24. The innermost backing sheet or member 22 of the pad 10 is provided with a perforated or weakened separating line 25 which extends in parallel spaced relation inwardly of the edge 24 on which the glue film is applied and divides the member 22 into a relatively narrow inner strip 26 and a somewhat wider outer strip 27. The strip 27 is adapted to be separated from the strip 26 by tearing along the line 25, after which it is discarded, leaving the pad 10 with the relatively narrow strip 26 interposed between the outer backing member 21 and the sheets 23.

The strip 26 is the same shape and somewhat smaller in dimensions than the corresponding dimensions of the rectangular aperture or slot 19 in the pad holder 11 and the length of the backing member 21 is no greater than the corresponding dimension of the aperture 19 so that when the strip 27 has been removed from the pad the backing member 21 may be passed through the aperture 19 into the pocket 20 between the base plate 12 and the cover member 15 to position the pad with the inner strip 26 in the aperture 19. The backing member 21 has a thickness corresponding approximately to the difference in thickness between the base plate 12 and the frame member 14 and the strip 26 has substantially the same thickness as the material in the cover sheet 15 so that the uppermost surface of the strip 26 is flush with the top surface of the surrounding top portion 18 of the cover sheet 15 thereby providing a smooth uniform supporting surface for the bottom sheets in the pad whereby such sheets may be conveniently written upon. The provision on the pad 10 of the backing member 21 and the inner strip member 26 and the provision on the holder 11 of the aperture 19 in the top cover portion 18 and the pocket 20 between the cover member 15 and the base plate 12 permits the pad 10 to be readily attached to the holder 11 and removed therefrom and insures that the pad is restrained against lateral shifting movement when it is properly positioned on the holder.

In order to insure that the pad 10 will not be pulled out of position when a sheet is removed, the holder 11 is provided with a locking arrangement for the pad which comprises an L-shaped locking slide 30 which is received in a guideway forming recess 31 provided in the frame member 14 at the top edge of the pad holder. The locking slide 30 is arranged with a horizontal body portion 32 in the guideway 31 which has an elongate aperture 33 for receiving a rivet 34 extending through the frame member 14 and the cover members 15 and 16 and limiting the movement of the locking member 30. The inner end 35 of the body portion 32 is pointed or beveled in the form of a knife edge and adapted to penetrate the edge 24 of the pad 10 when pressure is applied inwardly upon the flange 36 at the other end of the body portion 32. The locking slide 30 may, of course, be withdrawn so that the inner end 35 does not interfere with the positioning and removal of the pad 10 on the holder, as indicated in Figure 2.

An alternative arrangement may be employed for retaining the pad 10 in position on the holder with the outer backing sheet 21 seated in the pocket 20 which comprises placing one or more spots of pressure sensitive adhesive on the inner face of the backing sheet 21 so that when the pad is properly positioned on the holder with the backing sheet 21 seated in the pocket 20 and pressure is applied to the top surface of the pad, the backing sheet 21 will be adhesively secured to the inner

face of the top cover sheet 15. The adhesive employed is, of course, the non-setting type which permits the backing sheet 21 to be released from the cover member for removal from the holder by pulling on the exposed end 5 of the backing sheet 21. Also the plate 12 may have a coating or covering on its upper surface of resilient material, such as sponge rubber, to assist in holding the backing member 21 in the pocket 20.

The pad 10 may, of course, be used without attaching 10 the same to the holder 11 in which event, the portion 27 of the inner backing sheet need not be removed. The portion 27 of the inner backing sheet 22 may, of course, be easily detached from the portion 26 at any time by bending back the group of sheets 23 and breaking the 15 sheet 22 along the separating line 25, as indicated in Figure 4.

While particular materials and specific details of construction have been referred to in describing the form 20 of the pad and holder which is illustrated in the drawings, it will be understood that other materials and different details of construction may be resorted to within the spirit of the invention.

I claim:

1. A note pad holder comprising a relatively flat base 25 member having a top cover member of relatively stiff material, said cover member having an elongate generally rectangular slot of substantial width communicating with a pocket formed between the adjacent surfaces of the base member and the top cover member, and a note 30 pad on said holder, said note pad comprising a group of relatively thin flexible note sheets bound along one edge to the one edge of a two ply cardboard backing member, the inner ply of said backing member being substantially the same size and shape as said slot and being of a 35 thickness corresponding to the thickness of the material forming the cover member which adjoins the slot therein, the outer ply of said backing member being substantially the same size as said sheets so that it extends through said slot and is frictionally held in the pocket 40 formed between the base member and said cover member with said inner ply seated in said slot whereby the bottom sheet of said note pad rests on a flat surface, said note pad being held against movement on the holder by abutting engagement of the edges of said inner ply and the edges of the cover member which bound the slot 45 therein, and a locking element slidably mounted on said holder adjacent the slot in the top cover member which locking element is arranged with one end adapted to be moved into the slot for locking engagement with the lower portion of the note pad.

2. A holder for a note pad comprising a relatively flat base member and a cover member of relatively stiff material having substantial thickness, said cover member having a generally rectangular aperture of substantial width and depth, and a note pad having one dimension somewhat less than the length of the aperture and the other dimension greater than the width of said aperture, said pad having inner and outer bottom backing members, the inner one of said backing members being approximately the same size and shape as said aperture, 55 and being seated in said aperture, and the outer one of said backing members extending through said aperture and beneath a portion of said cover member so as to be held in frictional engagement between the base member and said cover member, said inner backing member having a thickness substantially equal to the thickness of the material of the cover member adjoining said aperture so that when it is seated in said aperture its edges engage with the edges of the cover member which define said aperture and its upper surface is substantially flush with the surface of the material in the cover member surrounding said aperture whereby the bottom sheet of said note pad rests on a smooth supporting surface and said note pad is held against movement on said holder 60 when a sheet is torn off.

3. A note pad which is characterized by a group of sheets bound along one edge to a backing member of substantially the same size as said sheets and a holder for said pad, said holder comprising a base member of substantial weight and having a relatively flat upper surface, a top cover of relatively thick and relatively stiff leather secured over said base member, said cover having an elongate generally rectangular slot of substantial length and width which provides an opening into a pocket of greater width formed between the base member and the cover, said note pad having an elongate strip on the inner face of said backing member which has substantially the same dimensions and shape as said slot and which has a thickness corresponding substantially to the thickness of the leather cover, said pad being positioned with said backing member extending through said slot and into said pocket so as to be frictionally held in the pocket between the base member and the cover, and said strip being seated in said slot so that it is in the plane of the leather cover and its edges engage with the edges of the leather cover around the slot whereby the pad is held against shifting relative to said holder and the bottom one of said sheets is supported on the substantially smooth surface which is provided by the upper surface of the cover and the upper surface of said strip.

4. A note pad holder comprising a relatively flat base member having a top cover member of relatively thick and relatively stiff material, said cover member having an elongate generally rectangular opening cut therein which is of substantial length in one direction of the holder and of substantial width in the direction normal to the length thereof, said opening communicating with a pocket formed in the space provided between the adjacent surfaces of the base member and the top cover member which pocket has a greater dimension than the opening in the direction normal to the length of said opening, and a note pad on said holder, said note pad comprising a group of relatively thin flexible note sheets bound along one edge to the one edge of a two ply cardboard backing member, said pad being arranged with the bound edge of the pad extending along the outer lengthwise edge of said opening, the inner ply of said backing member being substantially the same size and shape as said opening and being of a thickness corresponding to the thickness of the material forming the cover member in which the opening is cut, the outer ply of said backing member being substantially the same size as said sheets and having a substantially greater dimension than the inner ply

in the direction normal to the bound edge of the pad, said outer ply being positioned so that it extends through said opening and is frictionally held in the pocket formed between the base member and said cover member with said inner ply seated in said opening whereby the bottom sheet of said note pad rests on a flat surface, and said note pad is held against movement on the holder by abutting engagement of the edges of said inner ply and the edges of the cover member which bound the opening therein.

5. A holder for a note pad comprising a relatively flat rectangular base member and a cover member of relatively thick and stiff material, said base having a shallow recess in its uppermost face forming a pocket beneath substantial portions of said cover member, said cover member having a generally rectangular opening extending across the holder along the top forming edge thereof, said opening connecting with the upper portion of said pocket and forming an entrance thereto, and a note pad having inner and outer bottom backing members, the inner one of said backing members being approximately the same size and shape as the opening in said cover member and being seated in said opening, and the outer one of said backing members extending through said opening and beneath a portion of said cover member so as to be held in frictional engagement in the pocket between the base member and said cover member, said inner backing member having a thickness substantially equal to the thickness of the material of the cover member adjoining said opening and being positioned in said opening in the same plane as said cover member so that its upper surface is substantially flush with the top surface of the cover member surrounding said opening whereby the bottom sheet of said note pad rests on a smooth supporting surface and said note pad is held against movement on said holder by abutting engagement of the edge surfaces of the inner one of said backing members with the edge surfaces of the cover member around said opening.
